UNITED STATES PATENT OFFICE

PIERRE CORNIBERT, OF TURIN, ITALY, ASSIGNOR, BY MESNE ASSIGNMENTS, TO SÄCHSISCHE TEXTILMASCHINENFABRIK VORM. RICH. HARTMAN, AKTIENGESELLSCHAFT, OF CHEMNITZ, GERMANY, A JOINT-STOCK COMPANY OF GERMANY

PULL-THROUGH DRAWING FRAME FOR MEDIUM AND LONG FIBROUS MATERIAL, MORE PARTICULARLY, COMBED WOOL, ARTIFICIAL SILK, RAMIE

Application filed March 25, 1930, Serial No. 438,797, and in Germany April 5, 1929.

The present invention relates to a pull through drawing frame for fibrous material of medium and considerable length, more particularly combed wool, schappe, artificial silk, ramie, of the type wherein the sliver or ribbon is conveyed between the pair of feed rollers and the pair of delivery or drawing rollers by an endless conveyer band running over lower driven intermediate rollers.

10 Drawing frames having endless conveyer bands are known in which the conveyer band is arranged between the feed rollers and the delivery or drawing rollers and run over driven lower intermediate rollers. These known drawing frames are not suitable for drawing medium and long staple. In one known construction, a pressure top roller is arranged above the conveyer band whereby a preliminary draught is produced by the co-operation of the endless belt and pressure top roller on the one hand and the feed rollers on the other hand. This limits the length of the staple which can be effectively drawn. In another construction, the conveyer band merely serves the purpose of carrying the fibrous material from the rear pair of rollers to the front pair of rollers without retaining the floating fibres, and consequently an even drawing action is unattainable.

20 According to the invention, there is arranged between the lower intermediate driven rollers which serve for guiding the conveyer band, at least one additional lower guide roller for the conveyer band, two non-gripping top rollers co-operating with the additional intermediate lower roller. By this arrangement a very efficient guiding of medium and long fibres is attained and a very efficient slip-through and retarding passage is produced. The sliver or ribbon to be drawn is compelled to follow the curved path formed by the employment of the two intermediate top rollers and the intermediate lower roller, which results in an excellent guiding of the floating fibres, as any accidental displacement of these fibres is entirely avoided.

The accompanying drawing shows by way of example a construction embodying the fea-

tures of the invention in diagrammatic elevation.

a designates the frame in which the rollers of the drawing frame are mounted. *b*¹ and *b*² are the feed rollers and *c*¹, *c*² are the delivery or drawing rollers. Between these rollers are arranged the non-gripping pairs of rollers *d*¹, *d*² and *f*¹, *f*², the endless conveyer band *n* running over the intermediate lower rollers *d*² and *f*². Between the lower 60 rollers *d*² and *f*² is provided an additional lower intermediate roller *e* for guiding the conveyer band. Opposite the roller *e* are arranged two upper non-gripping rollers *g*¹, *g*² in such a manner as to form at this point 65 a curved or arc-shaped path, by which a very effective retardation of floating fibres is attained.

All the top rollers *b*¹, *c*¹, *d*¹, *f*¹, *g*¹, *g*² are guided by means of their pivot pins in grooves 70 of bearing blocks *h* which are adjustable upon rods *i* and may be fixed in the adjusted positions by means of set screws. The bearing blocks of the lower rollers *b*², *f*² and *e* are adjustably and fixably mounted in a similar manner in the frame *a*. The upper roller *c*¹ of the pair of drawing or delivery rollers is in usual manner loaded by means of a weight *m* for the purpose of obtaining the necessary pressure for drawing the sliver 80 or ribbon *k*. The sliver or ribbon is supplied to the feed roller pair *b*¹, *b*² through an eye or guide *o*. The conveyer band *n* is driven by the driven lower rollers and may be tensioned by adjusting the roller *f*².

I claim:

1. A pull through drawing frame for drawing medium and long staple, comprising in combination: a pair of feed rollers; a pair of drawing rollers; a conveyer band arranged between the said pair of feed rollers and said pair of drawing rollers; intermediate driven lower rollers for guiding and driving the said conveyer band; non-gripping top rollers co-operating with said intermediate lower rollers; an additional lower roller arranged between the said intermediate lower rollers for guiding said conveyer band; and two non-gripping top rollers arranged oppositely on both sides of the said additional 95 100

lower roller and co-operating with the additional intermediate roller and the conveyer band in forming a curved path for the conveyer band and the material to be drawn, substantially as described.

- 5 2. A pull through drawing frame for drawing medium and long staple comprising in combination: a pair of feed rollers; a pair of drawing rollers; a conveyer band arranged between said pair of feed rollers and said pair of drawing rollers for guiding and conveying the material to be drawn; intermediate rollers for supporting the said conveyer band at the ends; an additional lower roller arranged between the said intermediate rollers for guiding the said conveyer band; and two non-gripping top rollers arranged oppositely and on both sides of the said additional lower roller, said three last 10 mentioned rollers being so arranged as to guide the conveyer band and the material to be drawn in a curved path, substantially as described.
- 15 3. A pull through drawing frame for drawing medium and long staple, comprising in combination: a pair of feed rollers; a pair of drawing rollers; a conveyer band arranged between said pair of feed rollers and said pair of drawing rollers; intermediate driven lower rollers for guiding and driving said conveyer band; non-gripping top rollers co-operating with said intermediate lower rollers and three additional rollers arranged between the front and rear ends of 20 the conveying portion of the conveyer band in such a manner as to guide the said conveyer band and the material to be drawn in a curved path around a portion of one of these three rollers, substantially as described.
- 25 4. A pull through drawing frame for drawing medium and long staple, comprising in combination: a pair of feed rollers; a pair of drawing rollers; a conveyer band arranged between said pair of feed rollers and said pair of drawing rollers; intermediate driven lower rollers for guiding and driving said conveyer band; non-gripping top rollers co-operating with said intermediate lower rollers; an additional lower roller arranged 30 between the said intermediate lower rollers for guiding the said conveyer band; and two non-gripping top rollers arranged oppositely and on both sides of the said additional lower roller in such a manner as to 35 hold the whole portion of the conveyer band passing between the said two non-gripping top rollers in contact with the said additional lower roller, substantially as described.

- 40 5. A pull-through drawing frame for drawing medium and long staple, comprising in combination: a pair of feed rollers; a pair of drawing rollers; a conveyor band arranged between said pair of feed rollers and said pair of drawing rollers; intermediate driven lower rollers for guiding and driving 45 50 55 60 65 70 75 80 85 90 95 100 105 110 115 120 125 130

the said conveyor band; non-gripping top rollers co-operating with said intermediate lower rollers; at least one additional lower roller arranged between the said intermediate lower rollers so as to guide the upper portion of the conveyor band; and two non-gripping top rollers arranged oppositely the said additional lower roller, one to the left and the other to the right of the additional lower roller.

Signed at Turin, Italy, this seventh day of March, 1930.

PIERRE CORNIBERT.
